UNITED STATES PATENT OFFICE.

ACHILL BIPPART, OF NEWARK, NEW JERSEY.

DESIGN FOR A COLLAR-BUTTON OR STUD.

SPECIFICATION forming part of Design No. 28,628, dated May 17, 1898.

Application filed June 26, 1897. Serial No. 642,545. Term of patent 14 years.

To all whom it may concern:

Be it known that I, ACHILL BIPPART, a citizen of the United States, residing at Newark, county of Essex, State of New Jersey, have 5 invented a certain new and useful Design for a Collar-Button or Stud, fully described and represented in the following specification and the accompanying drawings, forming a part of the same.

10 The novel features in the present design relate to the shank of an integral collar-button having a circular back and a bar-shaped front.

15 The shank in the present design includes a flat foot and a rectangular head, both the foot and the head being tapered toward their junction. Such junction is at about the middle of the length of the shank, and the edges of the foot are inclined at a much greater angle 20 than the sides of the head. The shank is thus contracted at the middle of its length and expanded from such point toward both ends.

25 In the annexed drawings, Figure 1 is an elevation of the button, with the back in section, the cross-bar or front being viewed from one end. Fig. 2 is an elevation of the button, with the back in section and the cross-bar viewed from one side. Fig. 3 is a plan of the button; Fig. 4, a plan of the back, with the 30 shank in section at the junction of its head and foot. Fig. 5 is a plan of the cross-bar or front viewed from the under side, with the shank in section, as in Fig. 4.

35 All the figures are drawn upon an exaggerated scale to show the form clearly. The sections show a hollow construction.

40 A designates the back of the button, shown of circular form; B, the flat foot of the shank; C, the rectangular head of the shank, and D 40 the front of the button, formed of a cross-bar having its under side attached to the middle

of the head C. The cross-bar is formed of a flattened ellipsoid, with thin edges upon the upper and lower sides.

The plane of the flat foot B is at right angles to the axis of the bar-shaped front D, as shown in Fig. 3, and the foot B and the head C of the shank are both tapered toward their junction with one another, the edges of the foot being inclined at a much greater angle 50° than the sides of the head, thus making the foot of triangular shape, with its base attached to the back A and its apex attached to the head C. While the foot is flat or of much greater breadth than thickness, as shown in Fig. 4, the head is of square form, as shown in Fig. 5, or of substantially the same breadth and thickness, with its sides tapered in the same direction from the bar D toward the foot, the junction of the foot and head forming the 60 smallest part of the shank.

The essential features of the design are the flat foot and the rectangular head having a much greater thickness than the foot and of substantially the same width as the cross-bar 65 D, with the edges of the foot and the sides of the head tapered toward their junction about the middle of the length of the shank, so that the shank is smallest in the middle and expanded toward both ends from the middle 70 point.

Having thus described my design, what I claim is—

The design for a collar-button or stud substantially as shown and described. 75

In testimony whereof I have hereunto set my hand in the presence of two subscribing witnesses.

ACHILL BIPPART.
